CLAIM

The ornamental design for a channel reveal with ribbed and perforated flanges, as shown and described.

DESCRIPTION

FIG. 1 is a top perspective view of a channel reveal with ribbed and perforated flanges, showing our new design;

FIG. 2 is a bottom perspective view of the channel reveal with ribbed and perforated flanges of FIG. 1

FIG. 3 is a front elevational view of the channel reveal with ribbed and perforated flanges of FIG. 1;

FIG. 4 is a rear elevational view of the channel reveal with ribbed and perforated flanges of FIG. 1;

FIG. 5 is a left elevational view of the channel reveal with ribbed and perforated flanges of FIG. 1;

FIG. 6 is a right elevational view of the channel reveal with ribbed and perforated flanges of FIG. 1;

FIG. 7 is a top plan view of the channel reveal with ribbed and perforated flanges of FIG. 1; and,

FIG. 8 is a bottom plan view of the channel reveal with ribbed and perforated flanges of FIG. 1.

The broken lines in FIGS. 1-8 are included for purposes of illustrating portions of the channel reveal with ribbed and perforated flanges that form no part of the claimed design. The channel reveal with ribbed and perforated flanges is shown with a symbolic break in its length. The symbolic break is depicted using dash-dot lines and brackets. The appearance of any portion of the channel reveal with ribbed and perforated flanges between and including the break lines forms no part of the claimed design.

1 Claim, 6 Drawing Sheets
